UNITED STATES PATENT OFFICE.

HENRY A. FRAMBURG, OF BERWYN, ILLINOIS, ASSIGNOR TO H. A. FRAMBURG & COMPANY, OF CHICAGO, ILLINOIS, A CORPORATION OF ILLINOIS.

SUPPORTING MEANS FOR ELECTRIC-LIGHT FIXTURES.

1,214,667.

Specification of Letters Patent.

Patented Feb. 6, 1917.

Application filed October 27, 1915. Serial No. 58,254.

To all whom it may concern:

Be it known that I, HENRY A. FRAMBURG, a citizen of the United States, residing at Berwyn, in the county of Cook and State 5 of Illinois, have invented a certain new and useful Improvement in Supporting Means for Electric-Light Fixtures, of which the following is a full, clear, concise, and exact description, reference being had to the accompanying drawings, forming a part of 10 this specification.

My invention relates to supporting means for electric light fixtures and more particularly to means for supporting reflectors, 15 shades, bowls or the like, for systems of indirect lighting.

In most of the systems of lighting termed indirect or semi-indirect, a bowl of translucent material is utilized for concealing the 20 electric lights which are generally employed in such systems and for diffusing the light therefrom. These bowls are made of glass, porcelain, alabaster or the like, and in general, do not lend themselves readily to the 25 usual mechanical means for attaching chains, or the like, by which they are supported. It is inadvisable to attempt to perforate the glass, porcelain, or the like, of which the bowl is made, and rigid clamping 30 means are generally unsatisfactory as they are liable to fracture the bowl due to expansion and contraction or due to improper attachment.

A number of devices have been proposed 35 in the prior art for attaching the chains or supporting means by springs, but these devices are subject to the defects, that, it is impossible for a workman to hold the bowl and apply them without the assistance of a 40 helper. That is to say they require that two hands be used in spreading the springs and applying them. Another inherent disadvantage that I have found to exist in such devices is that the spring becomes sprung 45 or bent when the device is applied to the lip of a bowl and thereafter the device becomes useless.

The chief object of my invention is to provide a hanger which can be applied with 50 one hand and which will not become sprung by careless handling and it is also an object of the invention to provide a hanger which, while gripping the edge of the bowl with

a yielding pressure, will, by the action of the supporting means, namely, the chains or the like, tend to grip the bowl more securely.

In the accompanying drawings which form a part of the present specification, Figure 1 is a side elevation of the attaching means showing the manner in which one 60 form of my invention may be secured to a glass or porcelain bowl or the like, Fig. 2 is a front elevation of the outer plate or escutcheon. In this form of the device the candelabrum or bracket which is shown in 65 Fig. 1 is omitted, Fig. 3 is a rear elevational view of the structure shown in Fig. 2, Fig. 4 is a fragmentary view of a modification, Fig. 5 is an elevational view with parts broken away of a modification of my invention, Fig. 6 is a view of the hanger of Fig. 4 opened up, and Fig. 7 is a plan view of the structure shown in Fig. 2.

The glass or similar bowl 1, is generally provided with a restricted portion 2, forming 75 a groove upon the outside thereof near the top of the bowl. An ornamental plate or escutcheon 3, as shown in front elevation in Fig. 2, is provided with the wings 4 or 5 which rest in the groove and are held there- 80 in as will be described later. A tongue or lug 6 extends from the back of the escutcheon 3, adjacent the top thereof, and the holding member 7 embraces the tongue 6 and is pivoted thereto. The holding member 7 85 is provided with a finger 8 which presses against the inside of the bowl below the groove 2 in such manner as to hold the escutcheon 3 and the ears 4, 5 firmly against the bowl. A hook or similar supporting 90 member 9 is secured to the top of the holding member 7. The supporting member 9 which may be in the shape of a hook, is secured to the chain 10. The bowl 1 is supported by a number of devices spaced 95 around the edge and each is supported by a chain, the chain being attached at such a point as to tend to hold the finger 8 tight against the inside of the bowl. The holding member 7 is provided with a spring 11 for 100 pressing the finger 8 against the inside of the bowl and the tension on the chain 10 is of such a direction as to aid the finger 8 in holding the escutcheon against the outside of the bowl. A bracket 12 is secured to the 105 plate 3, this bracket bearing upon its outer

end, an ornamental lamp socket 13 having an electric lamp and a suitable shade 14, at the top thereof.

As above noted, the spring 11 normally holds the escutcheon plate 3 against the outside of the bowl with sufficient firmness to hold these parts together. The tension on the chain 10 increases the grip of the supporting means upon the bowl 1. It is not necessary that the bracket 12 and attached lamp socket 13 be secured to the plate 3 where it is desired to support merely the bowl 1.

In Fig. 4 I have illustrated a modified form of holding member 7'. In this case, the lug 6' which is secured to the escutcheon 3, instead of being formed as a thin tongue of metal, forms a round stud 15 which slides into the hollow barrel of the holding member 7'. The stud 15 is slotted to receive the end of the coil spring 16 which is held in place by means of a pin 17. The outer end of the spring 16 is secured to the holding member 7' in any suitable manner as for instance, by a loop 18 shown in Fig. 4. In this form of a device the holding member 7' is withdrawn longitudinally until the finger 8 is far enough removed to apply the device to the bowl 1 and the holding member is then released and is slid longitudinally over the stud 15 securely holding the finger against the inside of the bowl. It is obvious that when the holding member 7' has been withdrawn to clear the end of the stud 15, the same may be bent upwardly, in order to more readily apply the same to the edge of the bowl 1. (See Fig. 6).

In Fig. 5 I have illustrated the translucent bowl 20 as attached to a metal rim or reflector 21 by means of suitable supporting fingers 22 which are pivoted at 23 to the rim 21. The upper end of the finger member 22 is provided with means such as the arm 24, for attaching the same to the chain 10. The metal rim is provided with a downwardly extending flange 25 which projects into the bowl 20 and serves as a steady-ing means therefor. It is to be understood that the flange 25 does not need to fit closely within the edge of the bowl 20. A spring 11 is provided for holding the finger member 22 against the inside of the bowl, but the spring means is not necessary, the weight of the rim and the bowl tending to hold this part in place. It is to be understood that a number of the pivoted fingers 22, are provided around the inside of the rim member 21. I have shown the chains as attached to the holding or finger member, but it is to be understood that the advantages of ready applicability and freedom from being damaged are present no matter where the chain is attached.

The hanger shown in Figs. 1, 2 and 3 can be applied to the bowl with one hand by

grasping the hook 9 and the top of the plate 3 between the thumb and finger of one hand. The coil or hairpin springs 11 readily yield without being sprung, to admit the top of the bowl.

The form shown in Fig. 4 is first opened as shown in Fig. 6 and it can then be held and applied with one hand, no matter how thick the lip of the glass bowl is. It can be seen that a hanger constructed according to my invention can be opened up as wide as desired without damaging the spring.

I claim:

1. In a hanger for illumination bowls and the like, an external escutcheon member adapted to lie on the outside of the bowl, said member having a portion adapted to lie above the rim of the bowl, a holding member pivoted to said escutcheon member, said pivots being located intermediate the ends of both members whereby they both constitute levers of the first class, said holding member comprising a substantially horizontal portion and a gripping finger depending from the rear end of said horizontal portion, the forward end of said horizontal portion having a pivot part co-operating with a part on the escutcheon member, and having a suspending hook and resilient means for holding said holding member and said escutcheon member against opposite sides of the bowl, said horizontal member being adapted to lie immediately above the rim of the bowl.

2. A spring gripping hanger for illuminating bowls adapted to be applicable with one hand, said hanger comprising an external member and a gripping member, said members being pivoted to each other intermediate their ends to form levers of the first class, and spring means to hold said lower ends of the members with yielding pressure against opposite sides of the bowl, the upper ends of both members being adapted to be held together between the thumb and finger of the operator for positioning upon the bowl and a supporting chain or the like secured to the top of one of said members.

3. A spring gripping hanger for illuminating bowls adapted to be applicable with one hand, said hanger comprising an external member and a gripping member, said members being pivoted to each other intermediate their ends to form levers of the first class and spring means to hold said lower ends of the members with yielding pressure against opposite sides of the bowl, the upper ends of both members being adapted to be held together between the thumb and finger of the operator for positioning upon the bowl, said external member comprising a plate or escutcheon, said internal member comprising a substantially horizontal portion having a hook attached to the upper side and having a depending finger attached

at the rear end of the horizontal portion, the inner end of said horizontal portion comprising a pivot part coöperating with the corresponding part on the external member.

5 4. In a hanger for illuminating bowls and the like, an external member adapted to lie on the outside of the bowl, said member having a portion adapted to lie above the rim of the bowl, a holding member pivotally connected to said external member, the pivotal connection being made intermediate their length in order that both members may constitute levers of the first class, said holding members comprising a gripping finger and a suspending hook, resilient spring means for holding said internal holding member and said external member against opposite sides of the bowl, one of

10

15

said members having a substantially horizontal portion adapted to lie above the rim 20 of the bowl, said horizontal portion spacing said members apart to permit of a wide opening between both members in proximity to the pivotal connection, the tops of said members being adapted to be gripped between 25 the thumb and fingers of one hand so that pressure upon the tops of said members opens the lower ends of said members against the tension of said resilient means to permit the device to be readily positioned 30 upon the bowl.

In witness whereof, I hereunto subscribe my name this 22nd day of October, A. D. 1915.

HENRY A. FRAMBURG.
